(57) **CLAIM**

The ornamental design for a cigar humidor as shown and described.

DESCRIPTION

FIG. 1 is a front, top, and left perspective view of a cigar humidor showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1;

FIG. 8 is a rear, bottom, and right perspective view of FIG. 1;

FIG. 9 is a front, top, and left perspective view of the closed state thereof;

FIG. 10 is a front, top, and left perspective view of a second embodiment of a cigar humidor showing my new design;

FIG. 11 is a front elevational view of FIG. 10;

FIG. 12 is a rear elevational view of FIG. 10;

FIG. 13 is a left side elevational view of FIG. 10;

FIG. 14 is a right side elevational view of FIG. 10;

FIG. 15 is a top plan view of FIG. 10;

FIG. 16 is a bottom plan view of FIG. 10;

FIG. 17 is a rear, bottom, and right perspective view of FIG. 10; and,

FIG. 18 is a front, top, and left perspective view of the closed state thereof.

The broken lines shown in the drawings represent portions of the cigar humidor that form no part of the claimed design.

1 Claim, 18 Drawing Sheets
